UNITED STATES PATENT OFFICE.

JOSEPH J. MARKOVICH, OF UNIONTOWN, PENNSYLVANIA.

RAIL-TIE CHAIR.

1,405,607.

Specification of Letters Patent. Patented Feb. 7, 1922.

Application filed October 22, 1921. Serial No. 509,498.

To all whom it may concern:

Be it known that I, JOSEPH J. MARKOVICH, a citizen of the United States of America, residing at Uniontown, in the county of Fayette and State of Pennsylvania, have invented certain new and useful Improvements in Rail-Tie Chairs, of which the following is a specification.

This invention relates to certain new and useful improvements in rail tie chairs and has particular reference to the provision of improved means for supporting and securing railway rails upon cross ties of the usual wooden type.

15 The primary object of the invention is to provide an extremely simple and efficient construction of rail tie chair of the above kind for permitting securing of the rail to the tie in an expeditious manner.

20 Another object of the invention is to generally simplify and improve rail securing tie chairs.

With the above general objects in view and others that will appear as the nature 25 of the invention is better understood, the same consists in the novel form, combination and arrangement of parts hereinafter more fully described in connection with the accompanying drawings and in which like 30 characters of reference indicate corresponding parts throughout the several views.

In the drawing,

Figure 1 is a transverse sectional view taken through a rail and tie and a rail 35 chair constructed in accordance with the present invention,

Figure 2 is a top plan view of the rail chair shown in Figure 1 with the slidable rail engaging clips removed,

40 Figure 3 is a vertical sectional view taken upon line III—III of Figure 1,

Figure 4 is an enlarged perspective view of one of the slidable rail engaging clips shown in Figures 1 and 3,

45 Figure 5 is a view similar to Figure 1 showing a slightly modified form of the rail chair,

Figure 6 is a view similar to Figure 2 of the form of rail chair shown in Figure 5 and with the slidable rail engaging clips in place, and

Figure 7 is a fragmentary vertical sectional view taken upon line VII—VII of Figure 5.

55 Referring more in detail to the several views, the present invention consists of a

rail chair embodying a flat piece of metal or plate 5 adapted to rest upon the upper surface of a wooden tie 6 and to have the usual rail 7 rest thereon, the plate 5 being 60 provided along one side with a rigid or integral lip 8 formed to overhang and snugly engage the adjacent longitudinal edge portion of the adjacent base flange of the rail 7. Near the opposite side of the 65 plate 5 are provided a pair of transversely elongated slots 9 in which separate rail engaging clips 10 are slidably mounted, said clips including enlarged bases 11 engaging the enlarged portions of the slots 9 which 70 are provided by undercutting said slots as indicated by dotted lines in Figure 2 whereby the clips 10 are held against upward displacement. The clips 10 are of such form as to engage over the other base flange 75 of the rail 7 and the inner ends of the slots are enlarged as at 12 so as to permit the passage of the bases 11 of said lips after which the latter may be turned one-fourth revolution so as to be effectively held in 80 place. As shown in Figure 1, the plate 5 is disposed upon the tie 6 by sliding the plate 5 transversely under the rail 7 until the rigid lip 8 engages the adjacent flange of said rail and the movable clips 10 are 85 then forced inwardly into engagement with the other flange of the rail tie by driving spikes 13 through the slots 9 between the outer ends of said slots and the movable clips 10, thereby securing the plate 5 to 90 the tie and holding the clips 10 in engagement with the rail so as to effectively hold said rail down. To additionally secure the plate 5 to the tie, spike holes 14 are provided in the plate 5 outwardly of the rigid 95 lip 8 so as to permit spikes to be driven therethrough into the tie for holding the plate 5 down at this side of the rail. By providing the enlarged portions 12 in the slots 9, the clips 10 with their bases 11 may be 100 made integral so as to reduce the number of parts required to a minimum.

In the modified form of the invention shown in Figures 5, 6, and 7, the chair plate 5' is provided with the rigid or integral 105 overhanging lip 8' at one side and is also provided with the spike holes 14' outwardly of said lip 8'. At the opposite side of the plate 5' slots 9' are provided which are somewhat similar to the slots 9 of Figure 110 1 but which are not quite as long nor are they enlarged. By the use of this form of

slot, it is necessary that the slidable clips be made in separable sections and this is clearly shown wherein the clips 10' have separate bases 11' detachably secured to the 5 upper portion by means of a screw 15 which screw passes through a central opening provided in the base 11' and is threaded into the upper portion of the clip. In each construction, the upper portions of the clips are 10 connected by narrow necks with the bases with the overhanging portions of the clips engaging the base flanges of the rails, with the narrow necks disposed in the narrow portions of the slots and with the bases disposed 15 in the enlarged or undercut portions of said slots.

The manner of employing the chair shown in Figures 5 to 7 inclusive, is substantially the same as that set forth with respect 20 to the other form of the invention shown in Figures 1 to 4 inclusive except that the slidable clips of the first named form are assembled with the plate by removing the screws 15 and dropping the upper portions 25 of the slidable clips downwardly through the slots 9' after which the bases are disposed into the undercut portions of said slots from beneath and then connected by said screws.

From the foregoing description, it is believed 30 that the construction and operation

of the present invention will be readily understood and appreciated by those skilled in the art.

Minor changes may be made without departing from the spirit and scope of the invention as claimed. 35

What is claimed as new is:

A rail tie chair comprising a metallic plate adapted to be disposed flatly upon the upper surface of a rail tie and to have a rail rest 40 thereon, said plate having a lip along one side adapted to engage over one of the base flanges of said rail and having transversely elongated slots adjacent the other side with clips slidably held in said slots, said slots 45 being of such length as to permit spikes to be driven therethrough between the outer ends of the slots and the said clips for holding the latter in engagement with the other base flange of said rail, the said slots being undercut, and the said slidable clips embodying separable head and base members, the base members being beveled on their upper surfaces so as to fit snugly in the undercut 50 portions of the said slots of the metallic plate, the head members adapted to rest upon the metallic plate, and screw bolt connections for the head and base members. 55

In testimony whereof I affix my signature.

JOSEPH J. MARKOVICH.
